(57) **CLAIM**

The ornamental design for a nerve sizing device, as shown and described.

DESCRIPTION

FIG. 1 is a front perspective view of a nerve sizing device showing my new design;

FIG. 2 is a front view thereof;

FIG. 3 is a left side elevation view of the nerve sizing device according to my design;

FIG. 4 is a right side elevation view of the nerve sizing device according to my design;

FIG. 5 is a top plan view of the nerve sizing device according to my design; and,

FIG. 6 is a bottom plan view of the nerve sizing device according to my design.

The broken lines in the Figures depict surface ornamentation which forms no part of the claimed design.
